BLADE SHROUDING

Carl R. Soderberg, Weston, Mass., and William H. Lloyd, Philadelphia, Pa., assignors to Westinghouse Electric & Manufacturing Company, East Pittsburgh, Pa., a corporation of Pennsylvania

Application March 11, 1939, Serial No. 261,254

2 Claims. (Cl. 253—77)

This invention relates to elastic fluid turbines, and has for an object the provision of improved turbine blade shrouding which is particularly useful with high-temperature and high-pressure turbines.

Another object of the invention is the provision of turbine blades having integral spacing pieces at their free ends cooperating to form a shroud with a circumferentially-extending channel formed in the outer surface thereof, and tie members in the channel and welded to the spacing pieces at zones where danger of cracking is at a minimum.

A further object of the invention is the provision of blades having integral spacing pieces cooperating to form a shroud, the shroud having a circumferentially-extending channel of dovetail section in its outer surface closely receiving unstressed tie members of similar section, and welds securing the tie members to the spacing pieces.

These and other objects are effected by the invention as will be apparent from the following description and claims taken in connection with the accompanying drawing forming a part of this application, in which:

Fig. 1 is a side elevational view, with a portion thereof broken away along the line I—I of Fig. 2, showing a portion of a blade row embodying the invention;

Fig. 2 is a plan view of the structure shown in Fig. 1;

Figs. 3 and 4 are transverse sectional views taken along the lines III—III and IV—IV, respectively, of Fig. 2;

Fig. 5 is a plan view of a modified construction of the invention; and,

Fig. 6 is a sectional view taken along the line VI—VI of Fig. 5.

Referring now to the drawing more in detail, there is shown at 10 a blade-mounting member such as a turbine rotor carrying a plurality of blades 11, the blades having integral spacing pieces 12 at their outer ends which cooperate to form a shroud for the row of blades 11.

The shroud is provided with a circumferentially-extending channel 13 (Figs. 3 and 4) of dovetail cross-section in which are disposed a plurality of tie members 14 of similar section and having a metal-to-metal fit with the walls of the groove 13.

This metal-to-metal fit is important in that the tie members 14 should be in unstressed condition after insertion in the groove 13, and to this end, in actual assembly, the tie members 14 are

coated with lubricant, such as castor oil, and forced circumferentially into the groove. As an alternative method of obtaining the desired close fit without stressing of the tie members, the latter may be contracted by cooling in a well-known manner for a period immediately preceding insertion into the channel.

The tie members 14 are provided with a plurality of circumferentially-spaced openings 16 extending therethrough, the spacing of the openings 16 being such that they coincide with the centers of the spacing pieces 12. The openings 16 are filled with weld material 17, serving to autogenously connect the tie members to the spacing pieces.

Inasmuch as the tie members 14 are inserted into the groove circumferentially, it is necessary to provide a tie member of special design to be inserted last through the top of the groove 13. Such a tie piece is shown at the left in Fig. 2 and in Fig. 4.

As shown in these figures, a tie member 14a is split circumferentially (Fig. 4) and the two halves are inserted into the groove through the open top thereof. The tie member 14a is provided with openings 16a similar to the openings 16 in the tie strips 14. After assembly in the groove 13, weld metal 17a is applied in the openings 16a and the space between the two halves of the tie strip is filled with weld material 18 to provide an autogenous connection of the two halves of the tie member.

The modification shown in Figs. 5 and 6 differs from that of the preceding figures in that the openings 16 adjacent the ends of the tie strips 35 are omitted and the transverse ends of the tie strips themselves are welded directly to the spacing pieces which they overlie, as at 20.

While we have shown our invention in several forms, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In combination with a blade-mounting element, a row of blades mounted on said element, a spacing piece integral with the outer end of each blade, said spacing pieces cooperating to form a shroud for the row of blades, said shroud having an outer circumferential channel of dovetail cross-section, tie members of dovetail sec-

- tion fitting the channel, adjacent ends of adjoining tie members being aligned with the centers of spacing pieces which they overlie, said tie members being provided with spaced openings 5 extending therethrough and aligned with the centers of the intermediate spacing pieces, and weld material in said openings and at said ends for autogenously connecting the tie members to the spacing pieces.
- 10 2. In combination with a blade-mounting element, a row of blades mounted on said element, a spacing piece integral with the outer end of each blade, said spacing pieces cooperating to form a shroud for the row of blades, said shroud

having an outer circumferential channel of dovetail cross-section, a tie member of dovetail section fitting the channel, said tie member being comprised by two spaced strips and weld material in the space between said strips for autogenously connecting the latter, said tie member being provided with spaced openings therethrough and overlying the centers of the spacing pieces, and weld material filling said openings and autogenously connecting the tie member 10 to the spacing pieces.

CARL R. SODERBERG.
WILLIAM H. LLOYD.
